UNITED STATES PATENT OFFICE.

HENRY WILHELM, OF BROOKLYN, NEW YORK.

LOCK-CONTROLLING MECHANISM FOR SECTIONAL BOXES.

Application filed February 28, 1924. Serial No. 695,694.

To all whom it may concern:

Be it known that I, HENRY WILHELM, a citizen of the United States, residing at Brooklyn, in the county of Kings and State 5 of New York, have invented certain new and useful Improvements in Lock-Controlling Mechanism for Sectional Boxes, of which the following is a specification.

This invention relates to lock controlling 10 or operating mechanism for sectional boxes or compartments, an object of the invention being to provide improved locking mechanism whereby a plurality of boxes or compartments may be individually locked or 15 unlocked and also may be simultaneously locked or unlocked, and to provide a locking mechanism of this character simple in construction, and comparatively inexpensive to manufacture, and efficient in use, and 20 in which by means of a master lock all of the doors may be simultaneously locked or unlocked while each of the doors can be independently locked or unlocked.

The invention is useful in many fields as in 25 connection with lockers or drawers or letter boxes. In the present instance it is shown applied to a set of three boxes which could be used as letter boxes in the hall of an apartment house.

30 One of the objects of this invention is the provision of an improved lock controlling or operating mechanism which may be operated by a master mechanism or lock to simultaneously lock or unlock all of the 35 doors and which will permit the use of an ordinary locking mechanism for each door which can be individually manipulated to either lock or unlock the door.

In the drawings accompanying and forming 40 a part of this specification Fig. 1 is a front view partly in dotted lines illustrating the present improvement applied to a three-section letter box; Fig. 2 is a sectional view taken on line 2—2 Fig. 1 looking in the direction of the arrow; Fig. 3 is a sectional plan view; Fig. 4 is a detail perspective view of a part of the lock controlling mechanism; Fig. 5 is an enlarged sectional detail view of part of the lock controlling 45 mechanism; and Fig. 6 is also a detail view of a part of said lock controlling mechanism.

Similar characters of reference indicate 50 corresponding parts in the several views.

55 Before explaining in detail the present

improvement and mode of operation thereof, it is desired to have it understood that the invention is not limited to the details of construction and arrangement of parts which are illustrated in the accompanying 60 drawings, since the invention is capable of other embodiments, and that the phraseology which is employed is for the purpose of description and not of limitation.

In the present instance this improved lock 65 controlling or operating means is applied to a three section compartment or box which may be separately constructed and placed in position and which boxes are designated herein as 1, and each is provided with a 70 hinged or swinging door 2 having an ordinary spring lock 3 and lock bolt 3'.

The doors are shown in the present instance as of less height than the height of the boxes covering something over one half of 75 the height of the boxes. Each of these boxes can be individually opened by its particular key. Located in one of the compartments is a master lock 4, the bolt 5 of 80 which is pivotally connected to a swinging or oscillatory link 6 pivoted centrally thereof within the box as at 7 and the lower end of which as at 8 is pivotally connected to an operating bar 9 which is properly connected to a plurality of crank rods or rock 85 shafts 10, one for each box. As the crank or rock shaft mechanisms are similar a description of one will be sufficient. Each of these crank rods or rock shafts 10 is supported at its lower end by a suitable bearing 11 fastened in any suitable manner as by means of bolts 12 to the bottom of the box, whereby the rock shafts are maintained in proper 90 position. The operating bar 9 is connected to a crank 13 of each rock shaft, and these 95 cranks are located below the bottoms of the boxes. The crank rod 10 extends up through the box, the straight portion thereof being preferably located in a sleeve 14 to properly 100 guide the same to prevent the entrance of dust and dirt. Adjacent to its lock 3 the rock shaft is provided with a U-shaped portion or crank forming a nosing 15 for the latch or bolt 16 of its lock 3. The side of the box is projected or stamped outwardly 105 as at 17 to form a suitable crank nose receiving portion when the crank is rotated to unlock the door and the enclosing sleeve 14 is cut away adjacent to the crank nosing 15 to permit the proper swinging of the nose 110

15, and the cut away portion is bent into proper position as at 18 to form a stop to limit the throw of the crank nose 15. Thus the parts 17 and 18 act as stops at the opposite sides of the crank nose 15 to limit the movement of the crank nose. The crank rods being supported practically at the lower ends by bearings against longitudinal displacement may be properly termed floating rods, and the operating bar or rod 9 is likewise a floating bar, it being supported at intervals by angular portions 20 formed from a bar 21 which may be a part of the bearing supporting means 11 if desired. 10 The sleeves 14 are suitably fastened as by means of rivets to the sides of the boxes and may be if desired extended through the bottom to keep out the dust and dirt. 15 Thus from the foregoing it will be seen that when the crank nosings are in their proper positions all of the doors are locked but each lock may be individually manipulated by its proper key to withdraw its lock bolt 3' from the nosing. When it is desired to unlock all the locks simultaneously the master lock is operated and thereby all the crank nosings are shifted away from their lock bolts 3' thus unlocking the doors and when all of the doors are closed a reverse movement of the rock shafts will relock all the doors. Thus it will be seen that in the present improvement when the master means or lock is operated the crank nosings are shifted away from or toward the lock bolts 3' but when each individual lock is operated the lock bolt 3' thereof is itself shifted away from its crank nosing.

When ordinary spring locks having beveled latches are used if the master mechanism is operated to relock the doors and any of them remain open the door can be shut and locked by merely closing it since the beveled edge of the latch in striking the crank nosing would permit this. Of course if a dead lock is used this would not be possible and it would be necessary to have the doors all closed before the master lock is operated. When the boxes are used as letter boxes they are usually inserted in the space provided for that purpose and then a suitable molding as 22 is located around the edges of the boxes furnishing an ornamental finish therefor as well as a means for concealing the operating or controlling mechanism of the locks. For this purpose the box is provided around its edge with a beading 23 back of which a suitable beading 24 of the molding is located and of course the boxes are suitably fastened against displacement or movement within the spaces provided therefor.

From the foregoing it will be observed that each crank rod has a torsional movement which enables the crank rod to be

forced against the stops and thus held against rattling, and thus if one or more of the rods should be a little out of true it will still permit all the rods to be properly manipulated. It will be observed that the lower crank 13 of each crank rod has a greater arc of movement than the upper crank so that a partial movement of the crank 13 will throw the nosing crank sufficiently to unlock its lock.

It will furthermore be observed that as the locking mechanism is all within the door and overlapped as it were by the door there is no opportunity to insert a sharp instrument and shove back the latch as in an ordinary spring lock mechanism. In other words the crank nosing or keeper of the lock and the lock bolt are back of the door itself as will be seen in Fig. 1.

From the foregoing it will be seen that by the manipulation of the master lock the several rock shafts are simultaneously operated to shift the crank nosings away from the lock bolts of the several locks, and a reverse movement will relock all the doors. When it is desired to open any individual lock the lock bolt is withdrawn from the crank nosing. Thus if the boxes are used as letter boxes the postman by manipulating the master lock can unlock and relock all of the doors at the same time after inserting the mail in the boxes, and the individual owner of each box can by the insertion of the proper key unlock his own box without unlocking any of the others, so that the use of slots for the mail is done away with, these having been found to be objectionable since they permit the removal of mail by improper persons. It will also be observed that when this improved mechanism is used in connection with letter boxes it is not necessary that the whole front of the box be shifted or lowered in order to open all of the boxes. Therefore I have provided a very simple, efficient, and inexpensive locking device adapted for many uses as well as for letter box purposes.

It is to be understood that by describing in detail herein any particular form, structure, or arrangement, it is not intended to limit the invention beyond the terms of the several claims or the requirements of the prior art.

Having thus explained the nature of my said invention and described a way of constructing and using the same, although without attempting to set forth all of the forms in which it may be made, or all the modes of its use, I claim:

1. The combination of a plurality of doors, a key operated lock having a lock bolt, for each door, and master controlling means for locking or unlocking all of the doors simultaneously and including a rock

shaft mechanism for each lock having a crank formed nosing for each lock bolt.

2. The combination of a plurality of doors, a key operated lock having a lock bolt, for each door, and master controlling means for locking or unlocking all of the doors simultaneously and including a rock shaft mechanism for each lock having a crank formed nosing for each lock bolt, the crank formed nosing being shiftable toward or from the lock bolts to simultaneously lock or unlock the doors, and the lock bolts being shiftable away from the crank nosings when each is individually unlocked.

15 3. The combination of a door, a key operated lock having a lock bolt therefor, a rotatable shaft having a nosing adapted to cooperate with said lock bolt, and key operated means for rotating said shaft to shift the nosing relatively to said lock bolt.

20 4. The combination of a door, a key operated lock having a lock bolt therefor, a shaft having a crank adapted to form a nosing for the lock bolt, and key operated means connected to the shaft independently of said crank for operating said shaft to shift the crank toward or from said lock bolt.

25 5. The combination of a door, a key operated lock having a lock bolt therefor, a rock shaft having a pair of cranks, one forming a nosing for the lock bolt, and operating means connected with the other for rocking the shaft to swing the nosing toward or from the lock bolt.

30 6. The combination of a door, a key operated lock having a lock bolt therefor, a rock shaft having a pair of cranks, one forming a nosing for the lock bolt, and operating means connected with the other for rocking the shaft to swing the nosing toward or from the lock bolt, said last crank having a greater arc of movement than the nosing crank.

35 7. The combination of a door, a key operated lock having a lock bolt therefor, a floating rock shaft having a pair of cranks, one forming a nosing for the lock bolt, and operating means connected with the other for rocking the shaft to swing the nosing toward or from the lock bolt.

40 8. The combination of a door, a key operated lock having a lock bolt therefor, a floating rock shaft having a pair of cranks, one forming a nosing for the lock bolt, and operating means connected with the other for rocking the shaft to swing the nosing toward or from the lock bolt, said operating means comprising a floating bar and means for shifting it.

45 9. The combination of a door, a key operated lock having a lock bolt therefor, a floating rock shaft having a pair of cranks, one forming a nosing for the lock bolt, and operating means connected with the other

for rocking the shaft to swing the nosing toward or from the lock bolt, said operating means comprising a bar, means for supporting it at intervals, and means for shifting it.

70 10. The combination of a door, a key operated lock having a lock bolt therefor, a floating rock shaft having a pair of cranks, one forming a nosing for the lock bolt, and operating means connected with the other for rocking the shaft to swing the nosing toward or from the lock bolt, said operating means comprising a bar, angular means for supporting it at intervals, and means for sliding said bar.

75 11. The combination of a door, a key operated lock having a lock bolt therefor, a rock shaft having a crank formed nosing for the lock bolt, means for rocking said shaft to swing the nosing into position to cooperate with the lock bolt, and means for limiting the movement of said rock shaft.

80 12. The combination of a door, a key operated lock having a lock bolt therefor, a rock shaft having a crank formed nosing for the lock bolt, key operated means for rocking said shaft to swing the nosing into position to cooperate with the lock bolt, and means for limiting the movement of said rock shaft and comprising stop means at opposite sides of the nosing.

85 13. The combination of a box, a door therefor, a lock having a lock bolt for the door, a rock shaft having a crank formed nosing for the lock bolt, and means for rocking said shaft to swing the nosing into position to cooperate with the lock bolt, said box having a part thereof recessed to permit the swinging of the nosing in one direction.

90 14. The combination of a box, a door therefor, a lock having a lock bolt for the door, a rock shaft having a crank formed nosing for the lock bolt, means for rocking said shaft to swing the nosing into position to cooperate with the lock bolt, said box having a part thereof recessed to limit the swinging movement of the nosing in one direction, and means secured to the box for limiting the swinging movement of the nosing in the other direction.

95 15. The combination of a box, a door therefor, a lock having a lock bolt for the door, a rock shaft having a crank formed nosing for the lock bolt, and means for rocking said shaft to swing the nosing into position to cooperate with the lock bolt, said box having a stamped out portion to receive the crank nosing.

100 16. The combination of a box, a door therefor, a lock having a lock bolt for the door, a rock shaft having a crank formed nosing for the lock bolt, means for rocking said shaft to swing the nosing toward or from the lock bolt, said box having a stamped

out portion to receive the crank nosing, and means secured to the box for limiting the swinging movement of the nosing in one direction.

17. The combination of a box, a door therefor, a lock having a lock bolt for the door, a rock shaft having a crank formed nosing for the lock bolt, means for rocking said shaft to swing the nosing toward or from the lock bolt, said box having a stamped out portion to receive the crank nosing, and a sleeve enclosing said rock shaft and having a part thereof cut out to permit swinging movement of the crank nosing, and to form a stop for limiting the movement thereof.

18. The combination of a box, a door therefor, a lock having a lock bolt for the door, a rock shaft having a crank formed nosing for the lock bolt, means for rocking said shaft to swing the nosing toward or from the lock bolt, said box having a stamped out portion to receive the crank nosing, and a sleeve enclosing said rock shaft and having a part thereof cut out to permit swinging movement of the crank nosing, and to form a stop for limiting the movement thereof, the means for rocking said shaft comprising an operating crank, and a sliding bar connected therewith and means for operating said sliding bar.

19. The combination of a box, a door therefor, a lock having a lock bolt for the door, a rock shaft having a crank formed nosing for the lock bolt, means for rocking said shaft to swing the nosing toward or from the lock bolt, said box having a stamped out portion to receive the crank nosing, and a sleeve enclosing said rock shaft and having a part thereof cut out to permit swinging movement of the crank nosing and to form a stop for limiting the movement thereof, the means for rocking said shaft comprising an operating crank and a sliding bar connected therewith and a master lock for operating said sliding bar.

20. The combination of a plurality of doors, a lock having a lock bolt for each door, and master controlling means for locking or unlocking all of the doors simultaneously and including a rock shaft mechanism for each lock having a crank formed nosing for each lock bolt, and also having an operating crank having a greater arc of movement than the nosing crank, and a sliding bar connected therewith and with the master controlling means.

21. The combination of a plurality of doors, a lock having a lock bolt for each door, master controlling means for locking or unlocking all of the doors simultaneously and including a rock shaft mechanism for each lock having a crank formed nosing for each lock bolt, and also having an operating crank having a greater arc of movement than the nosing crank, a sliding bar con-

nected therewith and with the master controlling means, and means for floatingly supporting the rock shafts.

22. The combination of a plurality of doors, a lock having a lock bolt for each door, master controlling means for locking or unlocking all of the doors simultaneously and including a rock shaft mechanism for each lock having a crank formed nosing for each lock bolt, and also having an operating crank having a greater arc of movement than the nosing crank, a sliding bar connected therewith and with the master controlling means, and means for floatingly supporting the sliding bar.

23. The combination of a plurality of doors, a lock having a lock bolt for each door, master controlling means for locking or unlocking all of the doors simultaneously and including a rock shaft mechanism for each lock having a crank formed nosing for each lock bolt, and also having an operating crank having a greater arc of movement than the nosing crank, a sliding bar connected therewith and with the master controlling means, and means for floatingly supporting the rock shafts and the operating bar.

24. The combination of a plurality of doors, a lock having a lock bolt for each door, master controlling means for locking or unlocking all of the doors simultaneously and including a rock shaft mechanism for each lock having a crank formed nosing for each lock bolt, and means for limiting the throw of the rock shaft.

25. The combination of a plurality of doors, a lock having a lock bolt for each door, master controlling means for locking or unlocking all of the doors simultaneously and including a rock shaft mechanism for each lock having a crank formed nosing for each lock bolt, and means for limiting the throw of the rock shaft and comprising stop means at opposite sides thereof.

26. The combination of a plurality of boxes, doors therefor, a lock having a lock bolt for each door, a rock shaft mechanism for each lock having a crank formed nosing for each lock bolt, each box having a stamped out portion for the reception of the nosing and for limiting the swinging movement thereof in one direction, and also having means for limiting the swinging movement thereof in the opposite direction, and master controlling means for locking or unlocking all of the doors simultaneously and including a sliding bar connected with all of the rock shafts.

27. The combination of a plurality of boxes having doors, a lock having a lock bolt for each door, and master controlling means for locking or unlocking all the doors simultaneously and including a rock shaft mechanism for each lock having a crank

formed nosing for each lock bolt, each of said rock shafts having an operating crank having a greater arc of movement than the nosing crank.

- 5 28. The combination of a plurality of boxes having doors, a lock having a lock bolt for each door, and master controlling means for locking or unlocking all the doors simultaneously and including a rock shaft mechanism for each lock having a crank formed nosing for each lock bolt, and molding means for concealing a part of the operating mechanism.
- 10 29. The combination of a door, a key operated lock having a sliding lock bolt therefore, a rock shaft having a crank formed nosing for the lock bolt, means for rocking said shaft to swing the nosing toward or from the lock bolt, said lock bolt being independently shiftable toward or from the nosing.

- 15 30. The combination of a plurality of doors, a lock having a lock bolt for each door, a rock shaft having a crank formed nosing for each lock bolt, means for rocking all of said shafts simultaneously to swing the nosings toward or from the lock bolts, each of said lock bolts being independently shiftable toward or from its nosing.
- 25 31. The combination of a plurality of doors, a lock having a lock bolt for each

door, a rock shaft having a crank formed nosing for each lock bolt, and master lock means for simultaneously rocking all of said shafts to swing the nosings toward or from the lock bolts, each of said lock bolts being independently shiftable toward or from its nosing.

32. The combination of a plurality of doors, a lock having a lock bolt for each door, a rock shaft having a crank formed nosing for each lock bolt, and master lock means for simultaneously rocking all of said shafts to swing the nosings toward or from the lock bolts and including an operating crank carried by each of the rock shafts, and a sliding bar connecting all of said operating cranks with the master lock means.

33. The combination of a plurality of doors, a lock having a lock bolt for each door, a rock shaft having a crank formed nosing for each lock bolt, and master lock means for simultaneously rocking all of said shafts to swing the nosings toward or from the lock bolts and including an operating crank carried by each of the rock shafts, a sliding bar connecting all of said operating cranks, and a pivoted lever connecting said sliding bar with the master lock means.

Signed at Brooklyn, New York, this 26th day of February, 1924.

HENRY WILHELM.
